UNITED STATES PATENT OFFICE.

SIMON FRIGONE, OF CHICAGO LAWN, ILLINOIS.

WEATHER-STRIP.

No. 902,143.

Specification of Letters Patent.

Patented Oct. 27, 1908.

Application filed April 18, 1908. Serial No. 427,853.

To all whom it may concern:

Be it known that I, SIMON FRIGONE, a citizen of the United States, residing at Chicago Lawn, in the county of Cook and State of Illinois, have invented a new and useful Weather-Strip, of which the following is a specification.

The invention relates to improvements in weather strips.

10 The object of the present invention is to improve the construction of weather strips, and to provide a simple, inexpensive and efficient weather strip, adapted to be readily applied to an outside door, and capable of 15 cutting off the draft and preventing rain from blowing under the door.

With these and other objects in view, the invention consists in the construction and 20 novel combination of parts hereinafter fully described, illustrated in the accompanying drawing, and pointed out in the claims here- 25 to appended; it being understood that various changes in the form, proportion, size and minor details of construction, within the scope of the claims, may be resorted to without departing from the spirit or sacrificing any of the advantages of the invention.

In the drawing:—Figure 1 is a perspective view of a weather strip, constructed in 30 accordance with this invention and shown applied to a door, the latter being open. Fig. 2 is a vertical sectional view of the same, the door being closed. Fig. 3 is a sectional view of the weather strip, illustrating 35 the arrangement of the inner elastic strip and the outer hinged strip when the door is partly open. Fig. 4 is a detail view of a portion of the outer strip.

Like numerals of reference designate cor- 40 responding parts in all the figures of the drawing.

The weather strip is equipped with an inner elastic strip 1, and an outer hinged strip 2, secured to a door 3 by an attaching strip 4, which is preferably in the form of a piece of molding. The elastic strip 1, which is fitted against the outer face of the door, has its upper edge 5 secured to the attaching strip and arranged between the 45 same and the door. The attaching strip is provided in the lower portion of its inner face with a recess 6 to receive the upper edge of the elastic strip, and the end 1^a of the elastic strip adjacent to the hinged edge 50 of the door is preferably tacked, or otherwise secured to the same, as clearly shown

in Fig. 1. The lower edge of the elastic strip fits against the threshold or carpet strip 7 of the door sill and cuts off the draft and effectually excludes the weather. The 60 attaching strip has a lower projecting portion 8, over-hanging the upper portion of the hinged strip 2, which preferably consists of a strip of wood having a metallic covering 9. The upper edge of the hinged strip 65 is equipped with eyes 10, which are linked into eyes 11, depending from the over-hanging portion of the attaching strip.

The hinged strip protects the elastic strip from the weather and prevents the same 70 from becoming wet and freezing against the carpet or threshold strip, and it also bears against the elastic strip at a point below the upper attaching edge of the same, when the door is closed, as illustrated in Fig. 2 of the 75 drawing, and tends to hold the elastic strip against the door and the sill. The metallic covering not only strengthens the hinged strip, but increases the weight of the same so as to enable it to hold the elastic strip in 80 position for cutting off the draft.

When the door is opened, both the inner elastic strip and the outer hinged strip are supported in an elevated position above the floor by means of a curved bar 12, presenting 85 a smooth flat upper face and having its outer end 13 secured to the sill and seated in the recess thereof. The inner end 4 of the curved supporting bar is angularly bent to provide a foot, which is secured to the floor. 90 The door is easily opened and closed, and the weather strip effectually excludes the weather.

Having thus fully described my invention, what I claim as new and desire to secure by 95 Letters Patent, is:—

1. A weather strip including an inner flexible elastic strip arranged to fit against a door and a door sill, and an outer hinged strip arranged to bear against the elastic 100 strip to hold the same against the door when the latter is closed.

2. A weather strip including an attaching strip, an elastic strip connected at its upper edge with the attaching strip and adapted to fit against the outer face of the door and the door sill, and an outer hinged strip supported by the attaching strip and arranged to bear against the inner elastic strip when the door is closed. 105

3. In a weather strip, the combination of an attaching strip provided with depending 110

eyes and designed to be secured to the outer face of the door, an elastic strip having its upper edge secured between the attaching strip and the door and arranged to fit 5 against the latter and the sill thereof, a hinged strip provided with eyes linked into the eyes of the attaching strip and arranged to bear against the elastic strip when the door is closed, and a curved supporting bar 10 arranged to extend inwardly from the sill to

support the inner and outer strips in an elevated position when the door is opened.

In testimony, that I claim the foregoing as my own, I have hereto affixed my signature in the presence of two witnesses.

SIMON FRIGONE.
